UNITED STATES PATENT OFFICE.

CHARLES STANLEY RHOADS, JR., OF INDIANAPOLIS, INDIANA, ASSIGNOR TO WESTERN ELECTRIC COMPANY, INCORPORATED, OF NEW YORK, N. Y., A CORPORATION OF NEW YORK.

SIGNALING SYSTEM.

1,307,753.

Specification of Letters Patent. Patented June 24, 1919.

Application filed August 27, 1917. Serial No. 188,352.

To all whom it may concern:

Be it known that I, CHARLES STANLEY RHOADS, Jr., a citizen of the United States, residing at Indianapolis, in the county of Marion and State of Indiana, have invented a certain new and useful Improvement in Signaling Systems, of which the following is a full, clear, concise, and exact description, reference being had to the accompanying drawings, forming a part of this specification.

My invention relates to signaling systems, and has for its object the provision of means to decrease the current consumption necessary to the operation of substation signaling devices.

In one form my invention is particularly applicable in connection with telegraph systems wherein local relays and sounders are used. My invention of course can be desirably used in a plurality of different ways, but its general mode of operation will be apparent from its application to a telegraph system. In telegraph systems the relays and sounders are all operated on the closed circuit plan so that current is continually flowing except during the signaling operation, this current flow being continuous during all the time that the relay or sounder is idle and not in use.

I will explain this form which my invention may take more in detail by referring to the accompanying drawing illustrating the same diagrammatically.

In this drawing I show a telegraph key 1 coöperating with its contact 2 and adapted through the agency of the battery 3 to send impulses over the line wires 4 and 5. The system herein shown is of the customary series telegraph type, the conductor 4 being shown as metallic, although in practice it may be grounded as is frequently the case. A short circuit switch 6 is shown which closes the line circuit when the key 1 is not to be operated. I have only shown one key, although it is of course evident that any number may be inserted in the wires 4, 5.

I have shown three substations A, B and C. At substation A I have shown a relay 7 of the customary type having the armature 8 and its front contact 9. Normally, when the telegraph line is not in use a short circuit switch is closed so that the relay 7 is energized, and this is also true of the relays 7 at stations B and C. The armature 8 closes

the circuit through the battery 10 to the sounder 11. This sounder has the contact hammer 12 and the anvil 13, and likewise has the customary actuating coil 14. This actuating coil 14 is in series with a resistance 15.

I have found that I can get good results by having the sounder coils of four ohms resistance and the resistance 15 of twelve ohms resistance. Normally the resistance 15 is short circuited by the contacts 16 and 17 so that when the contact between the elements 8 and 9 is first established the battery 10 meets with but the resistance due to the sounder coils. After the hammer 12 has moved a considerable distance in response to the actuations of the coil 14, however, it engages the spring 17 and opens the short circuit about the resistance 15. This decreases the current consumption by nearly two-thirds. The inertia of the hammer 12 is sufficient not to objectionably influence the sound that it gives off when striking the anvil 13. During all the time that the hammer 12 rests against the anvil 13 but a small proportion of the current normally required to start the hammer in its movement is flowing from the battery 10. Thus should the system be idle for a considerable period of time, and it might sometimes be throughout the course of an entire night, the steady flow from the battery 10 is very materially reduced. The battery 10 in general is a gravity cell, the renewal of the active elements of which costs about a dollar.

In the normal operation of a system which I have had under observation the cell 10 would last two months. With the introduction of the contacts 16 and 17 I am enabled to increase the life of this cell to six months. At the substation B I have shown the active coil 14^a as occupying but a portion of the entire electromagnet, and have provided the electromagnet with a second winding 15^a which is periodically short circuited by the contacts 16 and 17, similarly to the manner shown at the substation A.

At substation C I have shown the contacts 16^a and 17^a as being operated directly from the relay armature 8^a. In this structure, however, the coöperating contact of the armature 8^a, namely the contact 9^a, is made in the form of a spring so that the circuit through the sounder magnet 14 is closed a

considerable period of time before the insulating projection 18 reaches the spring 17^a, whereupon the short circuit about the resistance 15 is opened.

- 5 From what has been described it will be readily apparent that I am enabled to operate the telegraph system at a great reduction in current consumption, thus reducing the cost of battery renewals.
- 10 Having thus described certain means for carrying out my invention others will readily suggest themselves, and what I claim as my invention is:

In a system of the character described the

Copies of this patent may be obtained for five cents each, by addressing the "Commissioner of Patents, Washington, D. C."

combination with a substation signal receiving device having an armature, a normally closed local circuit including said signal receiving device, a resistance in said circuit, a battery in said circuit, a relay for controlling said circuit having an armature, and 20 means under the control of the armature of said relay for short circuiting said resistance when said local circuit is open.

In witness whereof, I hereunto subscribe my name this 20th day of August, A. D. 26 1917.

CHARLES STANLEY RHOADS, JR.
